UNITED STATES PATENT OFFICE.

JOHN HONOR, OF SOUTHWEST, PENNSYLVANIA, ASSIGNOR OF ONE-HALF TO BENNIE WATZMAN, OF SOUTHWEST, PENNSYLVANIA.

CROSSING GATE.

Application filed October 19, 1923. Serial No. 669,590.

This invention relates to railroad crossing gates, and has particular application to the means employed for automatically closing the gate as a train approaches the crossing, 5 and subsequently opening the gate after the train passes the crossing.

More specifically stated, the invention makes use of an electrically operated motor forming part of the gate operating means, 10 the motor being included in a normally open circuit adapted to be closed by the train when the latter occupies a certain block in the trackway which is also included in the circuit, whereupon the motor is actuated to 15 close the gate, the circuit also including another block arranged at the opposite side of the crossing, so that the motor is actuated a second time to open the gate after the train passes the crossing.

20 In carrying out the invention, I provide the gate with an image which will represent either a flagman or a policeman, the image being adapted to be suspended from a gate with the arms extended, and equipped with 25 electric light bulbs for eyes, the bulbs being automatically illuminated when the gate is lowered.

The nature and advantages of the invention will be better understood when the following detailed description is read in connection with the accompanying drawings, the invention residing in the construction, combination and arrangement of parts as 30 claimed.

35 In the drawings forming part of this application, like numerals of reference indicate similar parts in the several views, and wherein:

40 Figure 1 is a side elevation of the gate showing the latter in a closed position by full lines, and in an elevated or opened position by dotted lines.

45 Figure 2 is a top plan view, showing the manner in which the bulbs of the image above referred to are illuminated when the gate is lowered.

Figure 3 is a view in elevation of the gate operating means.

50 Figure 4 is a view taken at a right angle to Figure 3.

Figure 5 is a view taken on the line 5—5 of Figure 4.

Figure 6 is a view taken on the line 6—6 of Figure 4.

Figure 7 is a view taken on the line 7—7 55 of Figure 4.

Figure 8 is a view looking at the opposite side of Figure 7.

Figure 9 is a sectional view taken on the line 9—9 of Figure 4.

Figure 10 is a diagrammatic view.

Referring to the drawings in detail, A and B represent the sections of the gate, each section being pivotally mounted upon a post 10. Each section includes spaced 65 parallel members 11 which are connected by pickets 12, the latter being pivotally connected with the members 11 to allow the gate sections to be elevated in the manner illustrated by dotted lines in Figure 1. Carried by the gate section A is an image 13 which may represent a flagman or a policeman, such as shown in this specific instance; the image being pivoted upon the section A so that it can occupy the positions shown in 70 Figure 1 when the said section is elevated or lowered. When lowered, the image is arranged at the meeting ends of the gate sections, thus occupying a position in the center of the highway or crossing where it can be readily seen by all approaching the crossing, and has its arms 14 extended as a warning to those in the vicinity of the crossing that a train is approaching the latter. This image is equipped with electric 75 light bulbs 15, which are used as eyes, and these bulbs are connected in circuit with a switch, the component parts of which are carried by the gate section A and its supporting post 10. In other words the gate section A supports a pair of spaced contacts 16 adapted to engage similar contacts 17 supported by the post 10, when the gate is in its lowered position, thereby closing the circuit to said bulbs, so that the image can 80 be readily seen at night time.

85 The spaced parallel members 11 of each gate section are fixed to the outer ends of shafts 18 and 19 respectively and as shown, said shafts are mounted for rotation in the 90 post 10.

95 Figure 4 is a view taken at a right angle to Figure 3.

adjacent post 10, and these shafts are rotated by an electrically operated motor to raise and lower the gate sections. These shafts are equipped with sprockets 20 over 5 which is trained an endless chain 21, so that both shafts are rotated in unison, although the shaft 19 is directly operated by the motor above referred to. It might here be stated, that each gate section is equipped 10 with a motor and an operating mechanism, but as this structure is the same for each gate section, I have only illustrated one gate operating mechanism. The electric motor is indicated at 22 and includes a worm 15 gear 23 carried by the shaft of the motor, and this gear meshes with a worm gear 24 fixed upon the shaft 25. Carried by one side of this worm gear 24 is an eccentric pin 26 which operates in a slotted link 27, 20 the lower end of which is connected with a toothed segment 28. As clearly illustrated in Figure 1, the teeth of this segment meshes with a pinion 29 carried by the shaft 19 of the gate section, and as the segment is 25 oscillated or swung in one direction, incident to the rotation of the worm gear 24, rotary motion is imparted to the shaft 19 of the gate section to lower the gate to an active position. It is of course manifest 30 that this segment is oscillated in one direction, when the worm gear makes one-half of a revolution, and as the said gear continues to make the other half of one revolution, the movement of the segment 28 is in 35 a reverse direction to elevate the gate section.

The switch which controls the motor is included in a normally open circuit, which also includes the blocks C and D of the trackway, these blocks being arranged at any desired 40 distance at either side of the crossing E as clearly illustrated in Figure 10. The source of current for this circuit is indicated at 30. The circuit also embodies a switch which includes a movable member in the 45 form of a disk indicated at 31 and loosely mounted upon the shaft 25. This disk when engaging the spaced contacts 32 closes the circuit to the motor, and in order to break the circuit at the proper interval of time, 50 the said disk 31 is provided with diametrically opposed notches 33 which normally lie directly opposite the contacts 32. Associated with this disk 31 is a ratchet wheel 34 and a plate 35 which supports a pivoted pawl 36, the latter engaging the teeth of the ratchet wheel as shown in Figure 8. Projecting from the plate 35 which is also loosely mounted upon the shaft 25 is an arm 37. 55 One end of this arm is connected to the adjacent end of a reciprocating rod 38, the latter being arranged directly above and actuated by a solenoid 39 when the latter is energized. The rod is normally spaced from the solenoid, and when attracted by the latter is 60 moves the arm 37 in a direction to cause the

pawl 36 to rotate the disk 31. This disk of course moves independently of the shaft upon which it is mounted, and when initially operated as just described, it moves into the position shown in Figure 8, wherein it will 70 be noted that the disk is engaging the spaced contacts 32, thereby closing the circuit to the motor 22. When the motor is put in operation the gate operating mechanism operates in the manner above described 75 to lower the gate to an active position. It is of course understood that the solenoid 39 is energized just as soon as the train enters upon either of the blocks C or D of the trackway, depending of course upon the direction in which the train is moving. Assuming that the train is moving in the direction indicated by the arrow in Figure 10, the train would of course first enter the block C, whereupon the current would flow 80 from the battery or source of energy 30 through the solenoid 39 to the rails of the block C, passing through the wheels of the train to the other side of the trackway, and thence through the wire 40 back to the battery 30. Consequently, the solenoid is energized to control the switch of the motor, and thus close the circuit to the motor, when the train enters on this block C. The block is arranged an appreciable distance away 85 from the crossing E so ample time will be provided for the closing of the gate before the train reaches the crossing. After the train passes the crossing and enters upon the block D, the circuit will be again energized 90 to continue the rotation of the shaft 25, and during the rotation of this shaft, the ratchet wheel 41 which is fixed on the shaft engages the pawl 43 carried by the other side of the disk 31, and causes the disk to continue 95 to rotate until it makes a complete revolution, at the end of which the notches 33 are positioned to separate the disk from the fixed contacts 32 thereby breaking the circuit to the motor. Of course during this 100 operation, the segment is being oscillated in a direction reverse to that hereinabove described, so as to turn the gate section to its elevated inactive position.

While it is believed that from the foregoing description, the nature and advantages of the invention will be readily apparent, I desire to have it understood that I do not limit myself to what is herein shown and described, and that such changes may be 110 resorted to when desired, as fall within the scope of what is claimed.

Having thus described the invention, I claim:

A device of the character described, 125 spaced shafts, a motor, operative connection between the motor and one of said shafts, means operatively connecting said shafts, spaced stationary contacts carried by the housing, a rotatable disk mounted for move- 130

ment relative to said contacts, said disk being formed with diametrically opposed notches, means initially moving said disk into engagement with the stationary contacts, means forming connection between the stationary contacts and the motor for energizing the same, means forming operative

connection between the motor driven mechanism and the disk to provide for rotation of the disk until the notches therein are 10 moved opposite the stationary contacts.

In testimony whereof I affix my signature.

JOHN HONOR.
